CHARLES H. OVERTON AND D. B. OVERTON, OF DOVER, NEW JERSEY.

Letters Patent No. 82,842, dated September 22, 1868.

IMPROVEMENT IN VALVE-GEAR FOR OSCILLATING ENGINES.

The Schedule referred to in these Letters Patent and making part of the same.

TO ALL WHOM IT MAY CONCERN:

Be it known that we, CHARLES H. OVERTON and D. B. OVERTON, of Dover, in the county of Morris, and State of New Jersey, have invented a new and improved Valve-Gear for Oscillating Engines; and we do hereby declare the following to be a full, clear, and exact description thereof, which will enable others skilled in the art to make and use the same, reference being had to the accompanying drawings, forming a part of this specification.

Figure 1 is a side view of an engine provided with my invention, the pillow-block for the steam side trunnion being removed to exhibit the parts more clearly.

Figure 2 is a top view of the engine and valve-gear.

The object of this invention is to provide means whereby a slide-valve may be applied to an oscillating cylinder with effective result.

The principal objection to the valve-gear of oscillating engines, as heretofore made, was, that the oscillating valves used would not wear uniformly, and the apparatus requisite for poppet-valves was too complex, becoming easily deranged, and being difficult to adjust.

By means of our invention, the common slide-valve, having a rectilineal reciprocating motion, may be employed, with perfect results.

In the drawings—

A is the steam-chest, interposed between the trunnion and the cylinder. In practice, the trunnion is cast in the steam-chest cover m. The side of the steam-chest is removed, to exhibit the valve B, which in this case is the common three-ported slide-valve.

The valve is actuated by means of an eccentric, C, or any other analogous device, as a cam-crank or the like, and the rod D thereof is provided with a hoop, G, which encircles and works with finished contact upon the reciprocating plate E. This plate is provided with an extension, H, connecting it with the valve-stem e, as shown, so that as the plate E is actuated to and fro by the eccentric-rod and hoop, the valve B will also be moved to and fro with it. By this arrangement, the "lead" can be adjusted by the eccentric as in the case of fixed cylinder-engines.

d is a guide-plate for the plate E, which latter is made with an opening having two parallel sides, n n, which fit with easy contact on the corresponding plane sides, n' n', of the guide-plate d, thus furnishing a means of guiding the plate E in a rectilineal motion when actuated by the hoop G, which works upon the said plate E.

The plate d is mounted upon a fillet or collar, b, of the steam side trunnion a, and may be keyed there, if desired, for it has no motion on the collar. The said collar bears no important function in the invention, being made simply as a bearing for the plate d, although the latter may with equal effect be mounted directly on the trunnion itself.

The steam is admitted through the trunnion a, and passes from the exhaust-port into an exhaust-cavity, leading to the opposite or exhaust-trunnion, in any suitable manner heretofore employed with oscillating engines.

Thus by our invention we obtain a rectilineal reciprocating motion, which enables us to use a slide-valve or valves on an oscillating cylinder in a simple and effective manner.

We will note that we contemplate, in certain cases, placing a steam-chest and valve at each end of the cylinder, in which case the central steam-chest A will be omitted, and the trunnion cast directly on the cylinder.

The hoop-plate E and plate d will encircle and work upon the trunnion, as before, and the plate E will be provided with one or more extensions, suitable for connecting it with the valve-stem of the two valves.

We desire to be understood as not limiting ourselves to the form of the plate d, that is to say, to the plane sides n' n', for the said plate d may consist of an annulus or collar, working with finished contact on the trunnion, and the points of its contact with the sides n n will furnish sufficient guide-surfaces for the plate E.

To permit the wearing of facets, the said annulus may be made to revolve slowly at each stroke of the valve.

Having thus described our invention, what we claim as new, and desire to secure by Letters Patent, is—

The arrangement of the hoop G, reciprocating plate E, and guide-plate d, with reference to the trunnion a of an oscillating cylinder, substantially as shown and described.

The above specification of our invention signed by us, this 6th day of June, 1868.

CHAS. H. OVERTON,
D. B. OVERTON.
